Inventor

John C. Zimmerman,

By his Attorney.

M. L. Collamer.

UNITED STATES PATENT OFFICE.

JOHN C. ZIMMERMAN, OF ELMIRA, NEW YORK.

SEAT FOR TRICYCLES.

SPECIFICATION forming part of Letters Patent No. 352,076, dated November 2, 1886.

Application filed July 15, 1886. Serial No. 208,094. (No model.)

To all whom it may concern:

Be it known that I, JOHN C. ZIMMERMAN, a citizen of the United States, residing at Elmira, in the county of Chemung and State of New York, have invented certain new and useful Improvements in a Child's Seat for Tricycles, &c.; and I do hereby declare the following to be a full, clear, and exact description of the invention, such as will enable others skilled in the art to which it appertains to make and use the same.

My invention relates to improvements in a child's seat for tricycles and tandems; and the object of my invention is to provide a strong, light, and serviceable seat for the purpose desired, which can be easily and quickly applied to or detached from the tricycle, and which, when in place, will support and carry the child at a point remote from danger from the working parts of the tricycle, and in such a manner as to afford a comfortable seat for the child and yet prevent its being thrown therefrom. I attain this object by means of the devices illustrated in the accompanying drawings, in which—

Figure 1 is a side view of a tricycle with my improved child's seat secured in place thereon. Fig. 2 is a perspective view of the clip, springs, and back of my improved child's seat. Fig. 3 is a front view of the same, the back and canopy being omitted. Fig. 4 is an enlarged bottom view of the supporting-clip. Fig. 5 is a rear view of the casting and back, showing the springs and canopy-supporting rod in position.

In the drawings hereto annexed and forming a part of this specification, A represents a tricycle, tandem, or other velocipede of a construction adapted to the use desired; but in the present instance I have shown an ordinary front-steering tricycle.

Upon the tubular front frame, B, of the tricycle I mount my improved child's seat by means of a strong metallic supporting-clip, C, which is of the following construction: c' is a flat base or body provided near its four corners with holes, for a purpose hereinafter set forth. Projecting downwardly from said body are two jaws, c', which curve inwardly toward and gradually approach each other throughout their lengths, whereby a semicircular groove or recess is formed between them, which groove

gradually tapers toward its front end. Through one of the jaws c' is formed a threaded hole, in which a thumb-screw, c'', works, the inner end 55 of the thumb-screw being reduced or pointed, as seen at c'''.

In attaching the child's seat to the tricycle, the jaws of the clip C are placed over the tubular frame B of the tricycle near its front end, 60 or where said tubular frame is of small diameter. The clip C is then slid back to the desired position, when it is fastened in place by turning the thumb-screw c'', whose point or reduced end indents or impinges against the 65 tubular frame and firmly secures the clip in place. Through the four corner holes in the corners of the supporting-clip C, above mentioned, are passed hooks or eyes D, of any suitable construction, and upon their lower protruding ends nuts are screwed against the body of the clip to keep them in place. Their upper or hooked ends rigidly clamp the lower ends 70 of two steel springs, E, which extend backward and upward from their points of support from one forward convolution, pass inside of the first forward bend, and extend upward at their free ends. A seat, F, preferably of wood suitably cushioned, is supported by and between these springs, being secured thereto 80 at the front bend of their forward convolution, and also at their inner upward rear bend. The seat is fastened to the springs by clips of any approved design, the upper bows, e, of the convolutions forming the sides thereof. 85 Two holding-straps, G, are fastened to the clip C, one on either side, and led up over the bows e of the springs, to which they are fastened at their points of crossing, whereby too great side motion of the springs is prevented; 90 and the ends of these straps are adapted to be buckled together over the child's lap to keep it in the seat and prevent its being thrown therefrom. These straps are provided with buckles between their points of fastening to 95 the clip on either side and to the springs, whereby they may be lengthened or shortened, to regulate them to a greater or less compression of the springs, according to the weight of the child.

H H represent steadyng-straps, which lead from the outer rear bends of the convolutions of the springs, and are adapted to be secured to any stationary part of the tricycle-frame—

such, for instance, as the lamp-support for preventing a too great forward and back motion of the child's seat.

Although I prefer making the straps G and H of leather, it will be understood that spiral or other springs or bands provided with means of longitudinal adjustment may be used.

J represents a malleable iron casting of suitable size and shape, and which is provided with vertical holes near each end and one through the center. The upper or free ends of the springs E are passed through the end holes and secured therein by set-screws j, passing through the back of the casting, whereby the latter is rendered vertically adjustable thereon. To the front or face of the casting J is secured the seat-back K by means of bolts k passing therethrough. The seat-back is thus rendered vertically adjustable by the adjustability of the casting.

Through the center hole in the casting J extends upwardly a rod, L, which is secured in said casting by a set-screw, k', also passing through the back of the casting, and whose upper end is bent forward and provided with an eye, l. To the upper end of the rod L is secured a suitable umbrella, canopy, or shade, M, for protecting the child from the weather.

Attached to the under side of the seat F, near its front edge, in the middle, is a metallic band or strap, N, which is bent downward and provided with a number of holes. A foot-rest, O, is secured to this band, near the lower end thereof, by a bolt passing through one of said holes, and may be adjusted higher or lower by setting the bolt in different holes.

What I claim as new, and desire to secure by Letters Patent, is—

1. In a child's seat for tricycles, &c., the combination, with the seat proper and supporting-springs therefor, of a clip, C, to which said springs are secured, said clip comprising a base, c, two downwardly-extending inwardly-curved jaws, c', and a set-screw, c², passing through one of said jaws and adapted to impinge against the frame of the tricycle for securing the clip in place.

2. In a child's seat for tricycles, &c., the combination, with the seat proper and supporting-springs therefor, of a clip, C, to which said springs are secured, said clip comprising a base, c, two downwardly-extending inwardly-curved jaws, c', said jaws gradually approaching each other throughout their lengths toward their front ends, whereby a tapering groove is formed between them, and a set-screw, c², passing through one of said jaws and adapted to impinge against the frame of the tricycle for securing the clip in place.

3. In a child's seat for tricycles, &c., the combination, with the seat proper and supporting-springs therefor, of a clip, C, to which said springs are secured, said clip comprising a base, c, two downwardly-extending inwardly-curved jaws, c', and a set-screw, c², passing through one of said jaws and adapted to impinge against the frame of the tricycle for se-

curing the clip in place, the inner end of said set-screw being reduced or pointed.

4. In a child's seat for tricycles, the combination, with a clip removably attached to the frame of the tricycle, of two springs secured to said clip, a seat and seat-back secured to said springs, and holding-straps G, attached to each side of said clip and to the upper bend or convolution of said springs, the upper or free ends of said straps being provided with a buckle and holes for fastening them together over the child's lap.

5. In a child's seat for tricycles, the combination, with a clip removably attached to the frame of the tricycle, of two springs secured to said clip, a seat and seat-back secured to said springs, and holding-straps G, attached to each side of said clip and to the upper bend or convolution of said springs, the upper or free ends of said straps being provided with a buckle and holes for fastening them together over the child's lap, said straps being longitudinally adjustable between their points of fastening to the clip and to the springs.

6. In a child's seat for tricycles, the combination, with a clip removably attached to the frame of the tricycle, springs secured to said clip, and a seat and seat-back secured to said springs, of steadyng-straps H, connecting said springs and a stationary part of the tricycle for preventing a too great forward and back motion of the seat.

7. In a child's seat for tricycles, the combination, with a clip removably secured to the frame of the tricycle, of two springs, E, secured to said clip, said springs extending backward and upward from said clip, forming one forward convolution, the upper bows of which constitute the arms of the seat, and extending upward at their free ends, and a seat and seat-back secured to said springs.

8. In a child's seat for tricycles, the combination, with a clip removably secured to the frame of the tricycle, springs secured to said clip, and a seat secured to said springs, of a casting, J, provided with holes for receiving the upper or free ends of said springs, set-screws for holding said casting in place on said springs, and a seat-back bolted to said casting.

9. In a child's seat for tricycles, the combination, with a clip removably secured to the frame of the tricycle, springs secured to said clip, and a seat secured to said springs, of a casting, J, provided with holes for receiving the upper or free ends of said springs, set-screws for holding said casting in place on said springs, a seat-back bolted to said casting, said casting being also provided with another hole extending vertically through its center, a canopy-support, L, therein, a canopy, M, secured to the upper end of said support, and a set-screw, k', for securing said support in position.

10. In a child's seat for tricycles, the combination, with a clip removably secured to the frame of the tricycle, of springs secured to said clip, a seat secured to said springs, and a foot-rest attached to the under side of said seat.

11. In a child's seat for tricycles, the combination, with a clip removably secured to the frame of the tricycle, of springs secured to said clip, a seat secured to said springs, and a foot-rest attached to the under side of said seat, said foot-rest comprising a metallic band, N, extending downwardly from the under front edge of said seat and provided with a number

of holes, and a foot-rest properly bolted thereto through one of said holes. 10

In testimony whereof I affix my signature in presence of two witnesses.

JOHN C. ZIMMERMAN.
